UNITED STATES PATENT OFFICE

2,532,006

DEVICE FOR ELIMINATING SQUEAKS FROM
BOARD STRUCTURES

Harland E. Beach, Valparaiso, Ind.

Application March 5, 1947, Serial No. 732,428

4 Claims. (Cl. 20—6)

1

My invention relates to anti-squeak devices for preventing, eliminating, or nullifying objectionable squeaks and noises developed in wooden or other similar structures, such as flooring and other building arrangements of like nature.

An important object of my invention is to provide an anti-squeak, or squeak correcting device, comprised of an adjustable supporting member, provided with locking means and suitable support means to secure the same to the sub-flooring under the joist separating the flooring proper from the said sub-flooring.

Another object of my invention is to provide a device of the aforementioned character which can be adjusted from time to time if, after its first attachment, squeaks develop from continual use or weight to which the flooring is subjected, or when the said flooring warps because of climatic conditions.

A further object of my invention is to provide a device of the aforementioned character which is simple in construction, practical in its use and operation, and of such elemental construction as to warrant economical manufacture thereof, in quantity production.

Other features and ancillary objects inherent in my invention will become apparent from an examination of the accompanying drawings, bearing further elucidation in the ensuing description wherein, like numerals designate like parts, and in which:

Fig. 1 is a cross sectional view of a flooring and sub-flooring showing my invention attached thereto.

Fig. 2 is a view looking in the direction of the arrows 2—2 of Fig. 1.

Fig. 3 is a sectional view taken substantially on the lines 3—3 of Fig. 1.

Referring to the various views, flooring made up of boards 10 and 11, jointed by means of the tongue and groove arrangement generally designated as 12, is common structure for flooring of a wooden construction. The said flooring is usually spaced from the sub-flooring 17, or the support 17, by means of cross joists 18. In order to attach my device, generally designated 4, it is necessary to bore out the sub-flooring 17 to form a suitable bored out portion 20, in order to provide sufficient clearance for the immobilizing support 8. The support 8 is a dished-out, funnel-like structure, or conical structure, having an extended supporting flange 9, placed directly under the boards that had developed noises or squeaks when subjected to weight of persons trodding thereupon.

2

The said conical structure 8 is provided with an opening 13, engaging rotatably the reduced tip or extension 7, emanating from the body 5 of the screw 5'; the body furnishing a resting shoulder 6 for the lower portion of the conical support 8. The screw 5' is securely and threadably attached to the flange structure 14, having an extended flange portion 15, which is secured to the sub-flooring 17 by means of the screws 16.

10 A lock nut 19 provides adjustment and secure locking in place for the conical support 8 under the flooring 10 and 11, preventing squeaks when the said flooring is caused to be deflected by weight exerted thereupon.

15 Sometimes such flooring develops squeaks even after a device, such as the one comprising my invention, is positioned thereunder due to warping of lumber, or other atmospheric conditions, which may affect the situation. In that event, the lock

20 nut 19 may be loosened and the screw 5' may be threaded to reach upwardly and exert a greater pressure by virtue of the conical element 8 against the lower surface, or underneath surface, of the flooring comprised of the sections 10 and 11.

25 Then the lock nut is tightened in place, or in the newly adjusted position, thus eliminating the squeak once again.

It will be understood that some changes may be made in the construction of the parts of my 30 improved support without departing from its essential features and purposes; hence, it is my intent to cover, by the instant patent application, any such changes which may be included within the scope of the appended claims.

35 Having thus described and revealed my invention, what I claim as novel, and desire to secure by Letters Patent, is:

1. In combination, a sub-flooring, flooring made up of jointed floor boards mounted thereon in spaced relationship with respect to the said sub-flooring, and an anti-squeak device comprising, a circular flanged element rigidly secured to the said sub-flooring, adjusting means secured to the said flanged element and terminating in a reduced shank portion, a frusto-conical supporting element secured rotatably to the reduced shank portion of the said adjusting means, and locking means to retain the said adjusting means in varied positions within the range of adjustment and disposed in contactual relationship under pressure directly below a point in a line of juncture of a pair of the said floor boards.

2. In combination, a sub-flooring, flooring made up of jointed floor boards mounted there-

on in spaced relationship with respect to the said sub-flooring, and an anti-squeak device comprising, a circular flanged element rigidly secured to the said sub-flooring, adjusting means secured to the said flanged element and terminating in a reduced shank portion, a frusto-conical supporting element secured rotatably to the reduced shank portion of the said adjusting means, and locking means to retain the said adjusting means in varied positions within the range of adjustment and disposed in contactual relationship under pressure directly below a point in a line of juncture of a pair of the said floor boards, the said frusto-conical supporting element being of smaller dimension than the said flanged element.

3. In combination, a sub-flooring, flooring made up of jointed floor boards mounted thereon in spaced relationship with respect to the said sub-flooring, and an anti-squeak device comprising, a circular flanged element rigidly secured to the said sub-flooring, adjusting means secured to the said flanged element and terminating in a reduced shank portion, a frusto-conical supporting element secured rotatably to the reduced shank portion of the said adjusting means, and locking means to retain the said adjusting means in varied positions within the range of adjustment and disposed in contactual relationship under pressure directly below a point in a line of juncture of a pair of the said floor boards, the said sub-flooring being bored out to a dimension affording clearance to the said frusto-conical supporting element but smaller than the perimetral dimension of the said flanged element thus providing a surface for securing the said flanged element thereto.

4. In combination, a sub-flooring, flooring made up of jointed floor boards mounted thereon in spaced relationship with respect to the said sub-flooring, and an anti-squeak device comprising, a circular flanged element rigidly secured to the said sub-flooring, adjusting means secured to the said flanged element and terminating in a reduced shank portion, a frusto-conical supporting element secured rotatably to the reduced shank portion of the said adjusting means, and locking means to retain the said adjusting means in varied positions within the range of adjustment and disposed in contactual relationship under pressure directly below a point in a line of juncture of a pair of the said floor boards, the said frusto-conical supporting element being of smaller dimension than the said flanged element, the said sub-flooring being bored out to a dimension affording clearance to the said frusto-conical supporting element but smaller than the perimetral dimension of the said flanged element thus providing a surface for securing the said flanged element thereto.
